UNITED STATES PATENT OFFICE

LEONARD S. SMITH, OF CINCINNATI, OHIO, ASSIGNOR OF ONE-HALF TO LEONARD S. SMITH, JR., OF CINCINNATI, OHIO; LEONARD S. SMITH, JR., EXECUTOR OF LEONARD S. SMITH, DECEASED

LAUNDERING APPARATUS

Application filed February 28, 1924. Serial No. 694,813.

This invention relates to apparatus for laundering wearing apparel, fabrics or articles of any kind.

The object of the invention is to provide improved apparatus of the kind stated which increases production for a given overhead charge, which largely reduces injury to the materials being laundered; and which also reduces the labor and simplifies the apparatus and manner of handling the materials during the several laundering operations and in transportation from machine to machine.

The ordinary commercial laundering of materials of this kind consists in washing the materials in a suitable machine, transferring them to a conveying truck or carrier, transferring the materials from the truck to a centrifugal extractor in which the moisture is eliminated by centrifugal action, returning the materials from the extractor basket to the same or a similar truck or carrier, conveying them to a shake-out table, or tumbler where they are shaken out, and then sorting them into lots for subsequent different treatments.

This prior method of laundering is objectionable for two reasons, first, because the inherent objections to a centrifugal extractor for eliminating moisture, and second, because of the labor involved in transferring materials to and from the truck. The centrifugal extractor is objectionable because of the high cost of initial installation, its delicacy of operation requiring adjustment and re-adjustment of materials in the basket to balance the same for proper spinning action, the danger of injury to materials which are inadvertently placed across the center and subjected to forces in opposite directions and thereby torn or mutilated, the natural tendency of materials under centrifugal force to enter the openings in the basket wall and the tight compacting of the materials, both of which result in injury thereto, either by pulling the pieces apart in removing them from the basket or in pulling the materials out of the basket apertures, and other inherent disadvantages natural to high speed machines of this character, such as danger to the operator, etc. The centrifugal extractor also

necessarily increases the number of operations in handling the materials, especially in transferring them from the trucks to the extractor basket and vice versa, not only thereby increasing possible injury to the materials, but also increasing liability of confusing the articles in different batches, where separation of batches is necessary for identification of the articles of different owners.

My invention aims to provide apparatus which has for its primary object the elimination of the centrifugal extractor, thereby not only eliminating its inherent disadvantages before stated, but also necessarily reducing the operations of handling the materials, especially in transfer thereof to and from the trucks, and in the water removing operation. This result is obtained in my invention essentially by the substitution for the centrifugal extractor of an expressing machine or press of suitable form in which the moisture is removed from the materials by a pressing or squeezing operation instead of by a centrifugal or rotary action. More particularly the invention provides a special form of expressing machine of which the truck or carrier forms a part, thereby eliminating the necessity of transfer of materials from the truck to the expressing machine and vice versa and consequently reducing the labor and avoiding the possibility of confusion of articles of different batches during the water removing operation.

Further objects of the invention will be more apparent from the description herein-after.

The invention comprises the apparatus hereinafter described and claimed.

In the drawings, Fig. 1 shows a front elevation of the washing and water removing machine; Fig. 2 is a plan view of the water removing machine; Fig. 3 is a sectional plan view thereof on the line 3—3, Fig. 1; Fig. 4 is a detail sectional plan view on the line 4—4, Fig. 1; Fig. 5 is a sectional elevation of the water removing machine on the line 5—5, Fig. 2; and Fig. 6 is a detail sectional elevation on the line 6—6, Fig. 5.

At the conclusion of a washing operation the load or the batch of materials is with-

drawn directly into a truck "F". This truck is shown as including a bottom 3 of suitable material, such as metal or a hard, strong wood of sufficient strength to stand the necessary pressure without distortion as will later appear. It is preferably also suitably perforated, such as by the provision of a plurality of elongated slots or openings 4 and is mounted upon wheels 5. One or more of the side walls of the truck, indicated at 6, are movably or separably connected thereto for convenience in removing the materials. For example, and as shown, all four of the walls of the present truck are hinged to the base, as at 7, so that any one or more of them can be released from the others and swung down laterally into horizontal position, but when all the walls are in vertical position they are held rigidly together in any suitable manner, such as by detachable latches 8 engaging pins 9. When in this position the four walls and bottom form a rigid container of box-like form capable of receiving a batch of materials in proportion to its size and of sufficient strength and rigidity to enable said materials, while in the box, to be subjected to a physical squeezing action or pressure for removing surplus liquid therefrom. While not illustrated the walls, of course, may be reinforced in any suitable manner and pressed one against the other by binding straps or bands if necessary.

Like the truck bottom its side walls are also conveniently perforated for discharge of the liquid, such as by forming therein a series of preferably vertically elongated slots 10.

The truck "F", containing the load of wet materials removed from the washing machine, is wheeled along the proper path, to the expressing machine "C" shown in detail in Figs. 5 and 6. This machine, so far as the production of squeezing pressure is concerned, may be of any suitable design similar to an ordinary baling or other press, and is therefore represented somewhat conventionally in the drawings. It includes a suitable frame 11, and a strong substantial base or lower platen 12, which may be a part of the building structure or foundation, but as shown is a solid metal or other part resting thereupon and provided with perforations 13 leading to one or more lateral channels 14 for conveying away the liquid, as will appear. In the frame is mounted a vertically movable upper platen or head 15, which is of the same shape and area in plan view as the opening in the box or truck "F". This head is shown as mounted on the lower end of a vertically movable screw 16 mounted to slide vertically without rotation in guides 17 to which it is connected by the spline 18 and capable of being moved vertically by a nut 19 forming a part of a bevel gear meshing with a bevel gear 20 on a shaft operated in any suitable manner, such as by power means

(not shown) or the hand wheel 22. The work engaging portion of the head 15 may be rigid, but preferably is of yieldable character so as to be self accommodating to any inequalities in a pile or mass to which pressure is being applied. As shown this platen is provided with suitable cushioning means, such as a flexible diaphragm 22a having its edges sealed to the edges of the head and forming with its face a chamber 23 to which fluid pressure, such as air pressure or the pressure of a liquid, may be supplied through passages 24 from a pipe 25 leading to a source of pressure.

As shown the bed 12 projects above the floor along which the wheels of the truck travel but is less in height than the under-clearance of the truck bed and is also narrower than the distance between its wheels, so that the truck can be rolled into position over the press bed and beneath the head 15, as shown in Fig. 5. To relieve the truck bottom from pressure and permit it to seat solidly upon the press bed the press bed is preferably provided with means for yieldably supporting the truck, such as shallow angle track members 26 of proper gauge for the wheels and upon which the wheels are rolled, said track members being supported yieldably by springs 27 in the floor.

A truck load of wet materials from the washer having been wheeled into position as shown in the press, the head or platen is moved downwardly by operation of the press mechanism, entering the box body of the truck, the upper edges of the walls of which are tapered or inclined as at 28, for guiding and centering the head, and then moves downwardly into engagement with the mass of wet materials. The first operation is, of course, to squeeze the whole mass downwardly and somewhat reduce its height. As the major portion of the moisture leaves the mass and drains out through the truck and press bed structures the mass becomes less and less compressible, and particularly may vary as to its compressibility in various portions, due to the manner of loading or the texture of materials. As this stage is reached the cushioned face of the head comes into play, yielding where the mass has the most density and accommodating itself to inequalities in the density of the mass, whereby the moisture is eliminated uniformly throughout the mass. The pressure produced may be of any desired degree to remove moisture to any extent desired. This operation can be carried out rapidly as compared with the water removing operation of a centrifugal extractor, which takes from 5 to 20 minutes according to the results desired, whereas the expressing operation can be performed in a matter of seconds and without any accompanying serious danger. Also the entire force of the plunger is in the vertical direction without any tendency to move the materials laterally into

5 apertures in the side walls of the press box or container and if materials enter the openings in its bottom they are removed in the same direction in which they enter, without liability of being injured. Also, the entire expressing operation is without liability of danger to the operator as compared with a centrifugal extractor.

10 When the expressing operation is completed the head is withdrawn and the truck with its contents is rolled away from the press, which is immediately ready for the next operation on the materials in the same or another similar truck.

15 The truck loaded with its compressed and relatively dry materials may now be conveyed to any suitable place for subjection of the articles to further treatment. Usually the materials are conveyed from the water 20 removing apparatus to the shake-out table, or a tumbler, where the materials are shaken out for subjection to subsequent treatments.

25 When removed from an extractor removal is necessarily a piece by piece operation, involving direct injury to the articles as before stated. By the present method the truck and contents may be directly conveyed to the shake-out table and the mass of compressed materials may be delivered thereto by merely 30 dropping one side of the truck and sliding the mass as a body upon the shake-out table, the truck being suitably elevated, as by a trestle, or other means for this purpose. At times the materials may be shaken out in a 35 simple rotary tumbler, without a drying effect, in which case the truck coming from the water removing machine is dumped directly into the tumbler.

40 In some cases batches of goods may be classified so that after the water removing operation, the batch may be directly conveyed to a machine for performing one definite subsequent operation, such for example as a dry tumbling operation. Here, also, the truck 45 with its contents may be rolled directly to the drying tumbler and by using a trestle or other means, not shown, the goods may be directly dumped as a mass from the truck into the drying tumbler, the rotation of the 50 drum of which will break up the mass and open out all of the individual articles without necessity of manual separation.

What I claim is:

55 1. Apparatus for expelling liquid from fabrics and the like, comprising a container for a batch of material, a pressing head movable in said container for preliminarily pressing the liquid from the batch, an expandible device within said container and 60 in contact with the material therein, and means for expanding said device.

65 2. Apparatus as in claim 1, wherein the expandible member is between the head and the material.

3. Apparatus as in claim 1, wherein the

expandible member moves down with the head.

4. Apparatus as in claim 1, wherein the expandible member is carried by the head in its movement.

In testimony whereof I hereby affix my ⁷⁰ signature.
